CLAIM

The ornamental design for a flooring support tray, as shown and described.

DESCRIPTION

FIG. 1 is a front-top-right perspective view of the flooring support tray, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear-bottom-left perspective view thereof;

FIG. 9 is a front-bottom-right perspective view thereof; and,

FIG. 10 is a front-top-right perspective view thereof.

The broken lines in the drawings are included for the purpose of showing portions of the flooring support tray that form no part of the claimed design.

1 Claim, 7 Drawing Sheets
